UNITED STATES PATENT OFFICE.

STARR H. BARNUM AND GUSTAVE WELTER, OF NEW HAVEN, CONNECTICUT, AS
SIGNORS TO THE BIGELOW COMPANY, OF NEW HAVEN, CONNECTICUT, A CORPORA-
TION OF CONNECTICUT.

TUBE-PLATE CONSTRUCTION.

Application filed August 31, 1925. Serial No. 53,546.

This invention relates to water tube boilers and particularly to the boiler units composed of two header members connected by a series of water tubes. The prior art as far as we are aware is fairly shown and discussed in the patent to Jeter 840,566, dated January 8, 1907. Our improvement is found in the special arrangement or connections of the water tubes with header members whereby there is less possibility for distortion as compared to prior art structures when the units are used in high pressure boilers. The construction by which this effect is obtained will be described in connection with the accompanying drawings, in which:—

Fig. 1 is a vertical cross section through a boiler unit embodying our invention but with the tubes not in the plane of the section omitted;

Fig. 2 is a view in the direction of the arrows taken on line 2—2 of Fig. 1; and

Fig. 3 is a view like Fig. 2 showing a slightly modified form.

As shown in the drawings the tube plate 1 in each header member is formed with a flange 2 for attachment to the cylindrical side wall of the header or drum. This tube plate is preferably made of cast steel and is provided on its interior surface with a plurality of upstanding cross webs 3 for a purpose to be described. The plate 1, flange 2 and cross webs 3 are all cast integral. As shown, the upper edges of the cross webs are just below the plane of attachment of flange 2 with header 4. The water tubes are attached to the tube plate in the usual manner except that as indicated in Fig. 2 these tubes enter the tube plate at the bottom portions of what amounts to a plurality of box-like compartments formed by the plate 1, flange 2, and webs 3. The tubes, immediately adjacent their connection with the tube plate are thus associated close to the intersections of integral right angled walls which are all arranged to resist distortion at the critical points where the tubes join the plate. In addition, these integral walls brace the joint where the flange 2 is attached to the header and prevent distortion at this point.

As pointed out in the Jeter patent above referred to, high pressure in units of the character shown has a marked tendency to

distort the central tubes under compression 55 and to distort the outside tubes under tension. As the pressure is increased there are serious distorting forces at work, one at the central tubes, one at the outer tubes and one at the joint between the flange and the 60 header. These forces tend to cause leaks at the tube plate. By arranging the tubes in the tube plate in proper distribution with relation to the box-like compartments described, so that all the tubes adjacent their 65 points of attachment with the tube plate are associated at the intersections of angularly arranged walls integral with the tube plate, and with like walls adjacent the joint made between the flange and header, all the 70 distorting forces above mentioned are met with effective resistance against actual distortion. Consequently, the tube plate can maintain its desired shape without springing 75 leaks between the tubes and the header either at the outside tubes, the center tubes, or the joint between the flange and header. The arrangement described is simple and yet most effective for the purpose of insuring 80 satisfactory attachments under high steam pressure between the water tubes, the tube plate, and the header member in units of the kind shown.

In Fig. 3 additional walls 5 are shown to indicate an extension of the idea of 85 associating the water tubes with the tube plates closely adjacent intersecting walls integral with the tube plate.

By actual test, it has been shown that the water tube unit made as we have described is much better able to withstand the work with high pressure than the prior art constructions heretofore used under like conditions.

What we claim is:—

1. A water tube boiler unit comprising header members or drums, water tubes nested between said drums, a tube plate for each drum comprising a flat sided wall provided with an integral flange attached 100 to the drum and integral cross walls extending inwardly from the plate, said walls being arranged to intersect one another, the plate, and flange whereby a plurality of substantial box-like recesses are provided in the 105 plate, the intersections of said walls being arranged adjacent the points of attachment of the water tubes with said plates.

2. A tube plate having an integral flange for attachment to the header or drum, integral bracing walls arranged across the plate from the flange, some of which walls intersect to form a plurality of substantial box-like recesses on the inside of the plate, said plate having its openings to receive the water tubes all arranged adjacent intersections formed by the plate the flange and said walls. 10
- 5 In testimony whereof we have affixed our signatures.
